UNITED STATES PATENT OFFICE.

HENRY B. COOLEY, OF NEW BRITAIN, CONNECTICUT, ASSIGNOR TO THE AMERICAN PAPER GOODS COMPANY, OF MONTCLAIR, NEW JERSEY, A CORPORATION OF NEW JERSEY.

DRINKING-CUP.

1,163,615.

Specification of Letters Patent.

Patented Dec. 7, 1915.

Application filed July 29, 1912. Serial No. 711,986.

To all whom it may concern:

Be it known that I, HENRY B. COOLEY, a citizen of the United States, and a resident of New Britain, in the county of Hartford and State of Connecticut, have invented a new and Improved Drinking-Cup, of which the following is a specification.

My invention relates more especially to that class of drinking cups that for sanitary purposes are constructed of paper or similar material, and an object of my invention, among others, is to provide a cup so constructed that it may be readily adapted for use in public places.

15 A form of cup embodying my invention and in the making and use of which the above object as well as others may be attained, is illustrated in the accompanying drawings, in which

20 Figure 1, is a side view of my improved cup. Fig. 2, is a like view seen in a direction at right angles from that of Fig. 1. Fig. 3, is a view illustrating one manner of use of my improved cup. Fig. 4, is a view 25 showing a modified form of construction.

Owing to the comparatively flexible character of drinking cups made of paper or like material, it is important that some means shall be provided to enable ready use 30 of the cups when required and especially when provided for the use of the public generally. Such a cup is illustrated in the accompanying drawings in which the numeral 5 indicates a cup composed of paper or like material, preferably tapered lengthwise 35 and closed at one end, forming a bottom 6. When made this cup is folded at the edges 7, producing a flat structure, and the paper forming the body of the cup is lapped on 40 one side, one edge underlying the other edge 8, and the overlapped parts being secured by a proper adhesive. The sides then have a semi-fold 9, produced therein, so that the cup may assume shape when desired for use. 45 The fold 8 is provided with a flap 10, projecting beyond the edge of the fold, the flap being creased at its base, as indicated by the dotted line 11, so that it may be opened outward from the body of the cup to form 50 a handle. An opening 12 is formed in the

flap to enable the cups to be properly placed for ready use and in a manner to occupy a minimum amount of space. This feature is illustrated in Fig. 3 of the drawings, in which it will be noted that the flaps 10 of 55 the cup projecting along the body of the cup, a number of the cups may be placed upon a hook 13 or like structure and the cups will lap one past the other so that this opening in the flaps may be made use of as an element 60 in enabling the cups to be deposited in a small space.

In the form of device shown in Fig. 4 the flap 10 is provided with an opening that may be reinforced as by an eyelet 14, and 65 the edge of the opening 12 may also be reinforced if desired.

The flap forms a ready means for handling the cup, and by providing an opening through the flap the latter may be tightly 70 gripped between the thumb and finger, thus enabling the cup to be firmly held. If the flap be scored at its base along the dotted line 11 it may be readily bent in position to form a grip and without such strain on 75 the parts as to separate the folded edges of the cup.

I claim:

1. A drinking cup composed of thin flexible material folded at its sides providing two 80 overlapping flaps one of which has an edge terminating at the lengthwise center of the cup, and a projection from said edge forming a handle, said projection having an opening.

2. A drinking cup composed of thin flexible material creased at opposite sides to permit the front and back to lie together and providing two flaps overlying one another, the edge of the overlying flap extending 90 along the lengthwise center of the back of the cup, and a projection from said edge adapted to lie against one half of the back of the cup, said projection having a hole whereby the cups may be nested when suspended on a support.

HENRY B. COOLEY.
